UNITED STATES PATENT OFFICE.

WALTER H. PIERCE, OF WATERTOWN, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed November 18, 1922. Serial No. 601,816.

To all whom it may concern:

Be it known that I, WALTER H. PIERCE, a citizen of the United States, and resident of Watertown, in the county of Middlesex and 5 State of Massachusetts, have invented an Improvement in Separable Fasteners, of which the following description, in connection with the accompanying drawings, is a specification, like characters on the drawings representing like parts.

This invention relates to separable fasteners. It is among the objects of the invention to provide a superior attachment of separable fasteners to the carrying fabric.

15 In the drawings, which show a preferred form of one embodiment of my invention:—

Figure 1 is a front elevation of a fastener;

Fig. 2 is a section on the line 2—2 thereof, being partly in elevation;

20 Fig. 3 is a section on the line 3—3 of Fig. 2, being partly in elevation; and

Fig. 4 illustrates the construction and relative arrangement of certain fastener parts prior to assembly thereof with their carrying fabric.

Referring to the drawings and to the preferred form of my invention selected for illustrative purposes, I have shown a conventional fastener typified by the stud 5 and 30 socket 6, containing a spring 7. The socket 6, prior to assembly thereof with its carrying fabric, presents (as best viewed in Fig. 4) a projecting hollow rivet 8 having a closed end 9. To secure the socket or any other fastener

35 part desired to the carrying fabric 10, I have provided a securing part including a cap or anvil 11 enclosing a cutting and clenching part 12, which presents centrally an aperture approximating in diameter the diameter

40 of the tubular rivet 8, as viewed in Fig. 4. The clenching part 12 is preferably supported against the anvil or cap 11 over a substantial area adjacent its outer edge, while its inner edge is thrown downwardly, prefer-

45 ably arcuately as indicated, to provide a cutting edge, which is preferably the inner edge 13, and also to provide, between the anvil or cap 11 and the cutting and clenching part, a space 14 into which that portion

50 of the fabric which is bodily separated therefrom by the cutting action between the rivet and cutting and clenching part 12 is forced and highly compressed. The high compression of this material has been found greatly to add to the security of the fastening and,

with a view to increasing this compression, I have found that the cutting and clenching portion 12 may be formed with a somewhat greater depression adjacent the aperture prior to assembly than is present after assembly. Where, as shown in the preferred embodiment of my invention illustrated, a shoulder 15 is provided by the socket immediately adjacent the bottom of the tubular portion 8, I have found that this shoulder 65 pressing against the cutting and clenching portion acts greatly to compress the cut-out material enclosed in the space above the clenching plate.

The construction illustrated presents other 70 advantages. Thus, during the initial portion of the crushing of the closed end tubular rivet, a considerable area or surface is presented against the anvil or cap 11, which considerable area greatly reduces the likelihood of 75 marking of the cap or of flaking enamel therefrom where any enamel or other coating is applied. During the initial portion of the rivet upsetting operation, the bearing against the inner surface of the cap is also somewhat cushioned by the interposed cut-out portion of the material, which material subsequently, under great pressure, flows into all corners of the space above the clenching plate. Any suitable form of hand or other 80 press may be used to supply the assembling pressure, the die above the cap preferably providing a close fit against a considerable portion of the surface thereof.

The cap 11 and clench plate 12 are preferably held together by a flanged-over portion 20 on the edge of the cap, such edge portion preferably coming opposite an adjacent surface of the socket or other fastener parts 6, so that the material at 21 is considerably compressed while the material lying inwardly of this base 21 is less compressed and therefore in a sense expanded within the recess provided beneath the clenching part 12. This greatly increases the 95 effectiveness of the grip on the fabric, which grip is always maintained by reason of the distortion of the parts. The compressed material within the cap serves to prevent any possible loosening of the clench between the 100 rivet and clench plate.

While I have illustrated and described my invention in connection with the attachment of a snap fastener socket, it will be understood that the features of my invention are 110

equally applicable to the combination of studs, grommets or other fastener parts, and that considerable changes may be made without departing from the scope of my invention, which is best defined in the following claim.

A fastener comprising, in combination, a fastener part having a closed end tubular rivet projecting from one side thereof and a 10 securing part presenting a cap or anvil portion and a cutting and clenching portion, said fastener part presenting adjacent the fabric a surface approximating in overall dimensions the over-all dimensions of said 15 cap, said cap flanged beneath said cutting and clenching portion and presenting fabric-

receiving spaces above and below the latter, said parts organized and operating when pressed together during assembly to fill the fabric-receiving spaces above said cutting 20 and clenching part solid full of detached fabric deformed under great pressure and to grip the main portion of the carrying fabric under great pressure between said flange and the adjacent surface of said fastener 25 part while providing in the space below said cutting and clenching part for the reception of a substantial area of the carrying fabric under substantially less pressure.

In testimony whereof, I have signed my 30 name to this specification.

WALTER H. PIERCE.
